RAIL FOR HEAT TREATING FURNACES

Henning Klouman, Michigan City, Ind., assignor
to Michiana Products Corporation, Michigan
City, Ind., a corporation of Indiana

Application June 13, 1936, Serial No. 85,089

4 Claims. (Cl. 263—6)

Iron pipe made by centrifugal casting and such like are usually heat treated to relieve any strains in and to anneal the metal before they are put in service. In a familiar furnace used for that treatment the pipes are rolled through the furnace chamber on several rails, sometimes required to align on top within plus or minus one sixty-fourth (1/64") of an inch. As the temperature changes are great and frequent, any tendency of the rails to distort is fostered and in consequence there has been much difficulty in maintaining the required tolerances.

Heretofore furnace rails have usually been in the shape of a channel with the flanges turned down and the web forming the supporting surface. When such a rail is made of heat resistant alloy (which cannot be rolled) it must be cast.

In a channel section the corners forming the juncture of the flanges and the web solidify and cool more slowly than the other extremities of the section.

Retarded solidification and cooling cause respectively internal shrinkage at the said juncture and a non-uniform rate of contraction in the casting as a whole, the immediate result of which is a tendency to bow the rail and distort the surface of the web from a true plane, sometimes raising one edge and sometimes lowering it, relative to the other. The pattern for a channel rail of heat resistant alloy can be arched to anticipate the sag, but the distortion is beyond control.

The principal object of this invention is to provide a rail that can easily be made true and that will maintain its supporting surface in use. This is accomplished by making the rail of a plurality of vertical webs connected at intervals by cross webs but preserving symmetry at every cross section.

A preferred embodiment of the invention is shown in the accompanying drawing in which—

Fig. 1 is a diagrammatical perspective of a heat treating furnace for cast iron cylinders;

Fig. 2 is a plan view of one of the furnace rails;

Fig. 3 is a side elevation of one of the rails and the upper portions of five supporting chairs, shown in section;

Fig. 4 is a cross section on the line 4—4 of Fig. 3, and

Figs. 5, 6 and 7 are diagrams illustrating distortions and deformations in channel shaped rails.

But the drawing and the description are used for the purpose of illustration only and the invention may be embodied in other forms.

The furnace chamber is enclosed by walls 10, a top 11, and a floor 12, the latter being equipped with several rails 13 running lengthwise through the furnace chamber and extending slightly above the surface of the floor.

The cylinders 14 to be treated are rolled along the rails by fingers 15 on conveyor chains 16 running over sprockets 17. The cylinders reach the furnace by rolling along approach rails 18, leading to the receiving end of the conveyor.

Each furnace rail 13 comprises four vertical webs 19 in spaced relation and integral with cross connecting webs 20, spaced along their length. The corners of the intersections are filleted, as indicated at 21 and 22, and the volume at the intersections is reduced by cylindrical holes 23 and 24.

At each end there are cross connecting webs 25 and the upright corners 26 are rounded, making it unnecessary to have the cylindrical holes 23 at the corners, but they are included where the intermediate vertical webs join the end webs.

As a specific example, the rail here shown is 84 inches long, 5 inches deep and 6 inches wide. The webs 19 are $\frac{3}{8}$ inch thick, leaving the spaces $1\frac{1}{2}$ inches wide. The fillets 21 are on a radius of $\frac{3}{4}$ inch and the fillets 22 are practically straight, lying at 30 degrees to a cross section through the center of the cylinders 23 and 24. The curve 27 at the left end, is on a 5 inch radius and the curve 28 at the right, on a 2 inch radius. The cross connecting webs are about $4\frac{1}{8}$ inches on centers.

The rails will be mounted to suit the conditions and personal preference. For example, the webs 19 may have transverse holes 29, 30, 31, 32 and 33 to receive the pins or bolts 34, by which the rails are made fast to the supports 35. Some engineers will prefer to have the holes 30, 31, 32 and 33 progressively elongated to allow for expansion and contraction.

The rails made according to this invention may be reversed when wear or injury has impaired one surface, thereby doubling the useful life of the rails. When the bolt holes are used and the design throws them away from the center line, two sets may be provided, as indicated in Figs. 3 and 4.

From the drawing it will be clear to those familiar with casting heat resistant alloy that every cross section of the rail illustrated is practically symmetrical and, hence, the distortion and deformity caused by unequal shrinkage and unequal contraction and expansion are prevented.

An alloy suitable for such rails is

	Per cent
Chromium	15 to 30
Nickel	8 to 40
5 And the remainder principally iron.	

However, it will be clear that the alloy is not of the essence of this invention.

In Fig. 5 the line 36 indicates roughly the camber required in a pattern to make a channel shaped rail substantially straight, and Figs. 6 and 7 illustrate how distortion lowers or raises one point with respect to the other. All these troubles are eliminated by the construction shown 15 in Figs. 2 to 4.

I claim as my invention:—

1. A rail for heat treating furnaces comprising a plurality of vertical webs extending lengthwise

of the rail with integral cross webs, and having every cross section symmetrical.

2. A rail for heat treating furnaces comprising a plurality of vertical webs of equal depth integral with cross connecting webs spaced at intervals, said vertical webs being of substantially uniform vertical dimensions throughout their lengths. 5

3. A rail for heat treating furnaces comprising a plurality of vertical webs of equal depth integral with cross connecting webs spaced at intervals, the junctures being marked by cylindrical holes. 10

4. A rail for heat treating furnaces comprising a plurality of thin vertical webs spaced wide 15 apart and rigidly connected by a plurality of cross webs at spaced intervals.

HENNING KLOUMAN.
